Inventor:

UNITED STATES PATENT OFFICE.

CLIFFORD VAN ALLEN, OF PITTSBURGH, PENNSYLVANIA.

CAR-RECORD-STATEMENT BLANK.

1,324,943.

Specification of Letters Patent. Patented Dec. 16, 1919.

Application filed December 11, 1917. Serial No. 206,717.

To all whom it may concern:

Be it known that I, CLIFFORD VAN ALLEN, a citizen of the United States, residing at Pittsburgh, in the county of Allegheny and State of Pennsylvania, have invented a new and useful Car-Record-Statement Blank, of which the following is a specification.

My invention relates to improvements in car record blanks, in which 1000 classifications appear on one sheet in front of the operator: and the objects of my improvement are, first, to provide a statement for any certain period, showing all car movements for that period in any railroad yard, and second, that such information shall be in 1000-classification form on each sheet complete.

I attain these objects by a statement illustrated in the accompanying drawing, in which Figure 1 illustrates a plan view of a statement sheet partly broken away containing 1000 blocks or sections, arranged 50 across the statement and 20 from top to bottom. The sheet is divided into sections 25 by intersecting vertical and transverse rulings. Fig. 2 illustrates an enlarged view of one of the sections. The sections are numbered 000 beginning at the upper left hand corner, as shown at "A," thence progressing from left to right in each horizontal section from the top to the bottom of the sheet, to 999 in the lower right hand corner, shown at "B" in the drawing. Car records to be entered in the manner shown in section numbered 001, shown at "C": for example, A1PRR446 would indicate: first hour of day, movement No. 1, and car P.R.R. No. 446001.

A 1 P. R. R. 466 in section 001 is similar 40 in some respects to any other car record entry. There are 26 letters in the alphabet and 24 hours in the day, therefore hours can be symbolized by letters, with two letters to spare. All movements possible or contemplated in or through a yard should be listed and numbered, and using an integral num-

ber it can be nicely sandwiched between the letter representing the hour and the letter or letters representing the car initial. It is only necessary to show the figures of a car 50 number, in its proper section, which are not shown in that section, as the number of the section calls for the remaining three figures. In case a car number would have only three or less number of figures, those figures 55 should be shown in the proper section bearing that number, and the figures underscored or encircled to show that they are the same as the number of the section.

It would be necessary to use only one 60 sheet at a time in any one yard, as more than one person can work on a sheet, whereas a book record can only be done very slowly by one operator entering, and several books have to be kept going at the same time to 65 keep up with the work. At most big yards the yard people would keep two or more sheets going at same time according to the direction of the traffic, as it would be liable to jumble the bills, etc., to have the operator 70 enter say, westbound and eastbound at same time, for when an eastbound bill gets into the westbound pile it becomes lost for a time, perhaps for eternity.

I claim:

A car record comprising a sheet divided by transverse and vertical intersecting lines into one thousand sections arranged in fifty vertical columns and each column containing twenty sections, the sections being numbered consecutively from 000 to 999, the lowest number appearing in the uppermost section of the left hand column, the numbers increasing by one in each section reading from left to right progressively in each 85 transverse row of sections from the top to the bottom of the sheet, the sheet being further provided with a blank column midway its length on which the sheet is adapted to be folded.

CLIFFORD VAN ALLEN.
